UNITED STATES PATENT OFFICE

2,507,505

SHOE LAST

William H. Doherty, Elmhurst, N. Y.

Application May 18, 1946; Serial No. 670,740

7 Claims. (Cl. 12—124)

1

This invention relates to an improved form of shoe last.

The principal object of the invention is the provision of a device of the character described which may be used in connection with shoes of different sizes and shapes and in connection with both right and left shoes.

Another object of this invention is the provision of a machine of the character described which is readily adjustable for shoes of different size and shape and which permits of ready mounting and demounting of the shoe relative thereto.

Preferred embodiments of this invention are shown in the accompanying drawing in which,

Fig. 1 is a vertical longitudinal section through the device.

Fig. 2 is a fragmentary plan view of the device.

In the embodiment of this invention, as shown in Figs. 1 and 2, a spreading type of toe block 120 is shown. This toe block comprises a permanently fixed or positioned inner part 121 flanked by two moveable side parts 122. Compression springs 123 tend to urge these several parts apart. It will be noted that the center piece 121 is connected to the two side pieces 122 by means of pivotally connected links 125 and 126. When the toe block 120 and the sole plate 130 are moved into position in the toe of shoe 25 a spreading action of the two side pieces 122 takes place as a consequence of any forced forward movement of the center piece 121. At the rear of the sole plate 130 may be formed a hand grip post 130'. This forced forward movement is effected by the following parts: A plate 131 is connected to the center piece 121 in a manner which permits of pivotal movement of the one relative to the other. This type of movement may be provided by forming a curved slot 132 in the center piece 121 and inserting forward curved end of plate 131 therein connected to the plate 131 by means of links 134 and 135 to heel plate 136 and counter block 137 pivoted to said heel plate. A screw 138 extends through an upwardly projecting part 139 of counter block 137 and engages fixed pins 140 therein. When the screw 138 is caused to rotate by means of knob 141 affixed thereto forward or backward movement of said screw is effected through the upwardly extending portion 139 of the counter block. The forward end of screw 138 is rotatably fixed to U-shaped member 144 and said U-shaped member is pivotally fixed to a second U-shaped member 145. The yokes of the two U-shaped members are opposite each other and it is by means of pins 147 extending through their legs that they are swivelly or

2

pivots connected to each other. The second U-shaped plate 145 is fixedly mounted on the plate 134 and indeed it may even be integral therewith.

5. It will be evident that when the knob 141 is turned in a clockwise direction forward movement thereof will be caused. When this occurs the forced forward action of the center piece 121 takes place. When the sides of the upper of the shoe 25 prevent forward movement of the side pieces 122 of the toe block an expansion movement thereof against said sides will take place.

While the invention has been described in detail and with respect to the preferred form shown in the drawings, it is not to be limited to such details and forms since many changes and modifications may be made in the invention without departing from the spirit and scope of the invention in its broadest aspects. Hence, it is intended to cover any and all forms and modifications of the invention which may come within the language or scope of any one or more of the appended claims.

I claim:

25. 1. A shoe last comprising a sole plate, a heel plate, a toe block mounted on the sole plate, a counterblock pivoted on the heel plate, and adjustable means extending between the counterblock and the toe block to alter the distance therebetween.

2. A shoe last which comprises a sole plate, a heel plate, a toe block mounted on the sole plate, a counterblock pivoted on the heel plate, pivotal connections between the toe block and the heel plate and adjustable connections between the counterblock and the toe block to alter the distance therebetween.

3. A shoe last which comprises a sole plate, a heel plate, a toe block comprising a center section fixed to the sole plate and lateral expandable sections on each side of the center section, links connecting the center and lateral connections, a counterblock pivoted on the heel plate and adjustable connections between the center section of the toe block and the counterblock to alter the distance therebetween.

4. A shoe last which comprises a sole plate, a heel plate, a toe block comprising a center section fixed to the sole plate and lateral expandable sections on each side of the center section, links connecting the center and lateral connections, a counterblock pivoted on the heel plate and adjustable connections between the center section of the toe block and the counterblock to alter the distance therebetween.

distance therebetween, and pivotal connections between the toe block and the heel plate.

5. A shoe last which comprises a sole plate, a heel plate, a toe block having a center section mounted on the sole plate and laterally adjustable sections on each side of the center section, toggle links connecting the center section with the lateral sections of the toe block, a counterblock pivoted to the heel plate, and adjustable connections between the counterblock and the toe block to alter the distance therebetween and expand the lateral sections of the toe block against the toe of the shoe as the center section is advanced.

10 6. A shoe last which comprises a sole plate, a heel plate, a toe block having a center section mounted on the sole plate and laterally adjustable sections on each side of the center section, toggle links connecting the center section with the lateral sections of the toe block, a counterblock pivoted to the heel plate, and adjustable connections between the counterblock and the toe block to alter the distance therebetween and expand the lateral sections of the toe block against the toe of the shoe as the center section is advanced, and pivotal connections between the toe block and the heel plate.

15 7. A shoe last which comprises a sole plate, a heel plate, a toe block having a center section fixed to the sole plate and adjustable lateral

5 sections on each side thereof, toggle links connecting the center section and the lateral sections, springs between the center section and the lateral sections normally tending to hold them apart a predetermined amount, a counterblock pivoted to the heel plate and adjustable connections between the counterblock and the center section to alter the distance therebetween.

10 WILLIAM H. DOHERTY.
